UNITED STATES PATENT OFFICE.

BEDORA H. WHITE, OF DETROIT, MICHIGAN.

BUCKLE.

REISSUED

Application filed March 26, 1926. Serial No. 97,702.

The invention relates to buckles for supporting garments and more particularly to a fastening device of this character for use in connection with the straps of garments 5 such as overalls and the like.

The particular construction of the buckle involves a frame with a spring slide associated therewith and one of the principal objects of this invention is to provide means 10 for detachably connecting this spring slide to the frame so as to facilitate the manufacture and assembly of the device. As a consequence of this the cost of production and of assembling is materially lessened and the 15 device rendered more practical and commercially satisfactory.

Various other objects, advantages and novel details of construction will be made more apparent as this description proceeds 20 especially when considered in connection with the accompanying drawings, wherein—

Figure 1 is a perspective view of a buckle as seen from the rear.

Figure 2 is a similar view with a strap of 25 a garment associated therewith.

Figure 3 is a vertical longitudinal sectional view through the buckle.

Figure 4 is a separated perspective view of the spring slide, and

Figure 5 is a view showing the invention 30 used in connection with the different form of buckle.

Referring now particularly to Figures 1 to 4 of the drawings, it will be noted that 35 there is illustrated a buckle comprising a main frame portion 10 having formed preferably integral therewith a button loop 11. However, as suggested in Figure 5, the invention may be equally advantageously associated with a buckle 10' in which the button loop 11' is formed as a separate member.

Associated with the frame 10 is a slide 12 here indicated as a spring slide, over and through which the strap S of the garment is 45 looped for adjustably securing the buckle thereto.

The present invention contemplates means for detachably connecting the slide 12 to the frame 10 and to this end the slide is provided 50 with hooked end portions 13 and 14 which are adapted to detachably and slidably engage the ends of the frame 10 in a manner most clearly illustrated in Figure 1. Considering the specific construction of the slide 55 12, it will be noted that it may be conveniently formed of a single length of mate-

rial such as wire bent into a substantial U-shape and having the closed end of the U-shape bent to provide the hooked portion 13, while each of the free ends are bent to 60 form the hooked portion 14. The hooked portions 13 and 14 are so formed that the intermediate leg portions 15 and 16 of the slide lie substantially intermediate the plane of the hooked end portions or in other words, 65 in a plane substantially coincident with the axes of the hooked end portions 13 and 14. In this manner the accidental separation of the detachable slide from the frame 10 after assembly is prevented as the legs 15 and 16 70 of the slide lie in the same plane as the longitudinal sides of the frame 10. In practice the strap S is adapted to be passed between the legs 15 and 16 of the slide 12 and thence over the upper leg 15 and for this purpose 75 this leg is formed with a laterally off-set portion 17 for clamping engagement with the strap in cooperation with the other leg 16.

While the slide 12 may be assembled with 80 the frame 10 in any one of several different ways, I have found that one convenient manner of assembly consists in first engaging the hooked ends 14 of the slide with one end of the frame 10, with the slide in an angular 85 position but in a plane substantially parallel to the plane of the frame 10. Thus, the hooked end 13 is disposed adjacent the corner of the frame 10 so that this hooked end may be slid axially of the end of the frame 90 10 and into engagement therewith as shown in Figure 1. During this movement it is necessary, however, to slightly flex the legs 15 and 16 of the slide so that they will clear the adjacent longitudinal side of the frame 95 10. When, however, the slide 12 has been moved to a position substantially as illustrated in Figure 1, the legs 15 and 16 may be permitted to spring back to their normal position where accidental disengagement of 100 the parts is prevented in the manner aforesaid.

The manner of connecting the slide 12' shown in Figure 5 with the frame 10' is identical with that just described so that 105 no detailed description is necessary.

While the slide 12 has been shown and described as a spring slide substantially similar in construction to that shown and claimed in my prior Patent No. 1,444,893 110 dated Feb. 13, 1923, still the principles of this invention are applicable and may be

utilized with facility in connection with a slide or other cooperating element of a buckle of this character, wherein the slide member is not resilient as in the illustrated construction. Therefore, it should be understood that reservation is made to make such changes in the details of construction as may come within the purview of the accompanying claims.

10 What I claim as my invention is:

1. In a buckle of the class described, a frame member and a spring slide connected thereto, the said slide comprising a single length of material bent to form a U-shaped member, the closed end of the U-shaped member being bent to form a hook detachably engageable with the frame member and the open end of the U-shaped member being bent to form a pair of hooks separately detachably engageable with the frame member.

2. In a buckle of the class described, a frame member, and a U-shaped spring slide connected thereto, the said slide having a body portion lying throughout its length in the plane of the frame, and end portions

bent toward each other to resiliently and detachably engage the frame member.

3. In a device of the character described, a frame and a spring slide detachably connected thereto, the said slide including leg portions spaced longitudinally of the said frame and having end portions adapted to hook around the frame and resiliently held in engagement therewith, one of the said leg portions being provided with a laterally offset clamping portion arranged substantially in the plane of the frame.

4. In a buckle of the character described, a frame, a separate slide adapted for sliding engagement on the said frame, the said slide including leg portions joined to each other at one end and spaced apart at their opposite ends, the said leg portions being spaced longitudinally of the said frame and being yieldably held in spaced relation to each other, the said end portions of the slide being bent toward each other and being adapted for detachable snap-on engagement with the said frame.

In testimony whereof I affix my signature.

BIRDORA H. WHITE.
